within the impeller of more definite or localized outwardly moving streams of liquid which more effectively move the gas outwardly as it is drawn into the center of the impeller. However, this does not seem to be a complete explanation as similar results did not follow from other structural changes which would similarly affect the liquid flow in the impeller.

Fig. 1 is a partly diagrammatical vertical section showing illustrative apparatus embodying the present invention, the section being taken approximately on the line 1—1 of Fig. 2.

Fig. 2 is a horizontal section taken in general on the line 2—2 of Fig. 1, a portion of the hood being broken away to expose the construction beneath it.

Fig. 3 is a vertical section showing the impeller only, the section being taken approximately on the line 3—3 of Fig. 1.

A tank 1, adapted to contain the liquid to be processed, is provided with a suitable valved inlet and outlet pipe 2 and with an overflow pipe 3. A plurality of rods 6 (four shown) depend from a superstructure (not shown) and suspend a stationary flow controlling structure designated as a whole by 7. A depending vertical shaft 9 carries and supports a rotary impeller designated as a whole by 10. Surrounding the shaft 9 is a gas conduit 19 through which gas is adapted to be inducted. The support and motor drive for shaft 9 and the support for gas conduit 19 and rods 6 may be of any suitable type as, for example, that disclosed in my prior Patent 1,976,956.

The stationary structure 7 comprises a hood member or ring 12 shaped much like the outer portion of an ordinary tin wash basin turned upside down. The hood member 12 may be cast of metal and integral with it there may be formed curved deflecting blades 13 which extend vertically downwardly from the hood 12. The hood may be provided with apertured bosses 14 (four shown) adapted to receive and be clamped to the rods 6 to support the stationary structure 7 and to provide for its accurate vertical location with respect to the impeller. The hood may also be cast with bosses 4, 4, which are used only in cases where it is desired to sever the hood ring along line 8, 8 so that the halves can be inserted into a tank through a relatively small manhole. In these cases, the bosses 4, 4 are drilled and tapped to receive bolts for clamping the two halves of the hood ring together. The hood 12 is provided with a central hole 16 which surrounds the bottom of conduit 19, thereby providing an annular liquid inlet port 17.

In operation the tank is filled with liquid to be treated (e. g. vegetable oil) to a depth which will completely submerge the structure 7, giving a liquid level such as that illustrated by line 15. When the impeller is rotated, it draws liquid upwardly from the bottom and also draws liquid downwardly from the top through annular port 17. The flow of liquid through the impeller creates a low pressure zone adjacent the hub of the impeller. Thus, gas is drawn through conduit 19 and is entrained with the liquid so that the impeller blades 29 cause streams of mixed gas and liquid to flow outwardly in a substantially horizontal direction to strike deflector blades 13 and be projected downwardly by hood 12. The main paths of circulation are as indicated by arrows A, C, and the auxiliary paths as indicated by arrows A, B.

The impeller shown is of the forward discharge type and in accordance with the present inven-

tion the blades 29 are provided with trailing horizontal fins 30. These fins are preferably on the lower edges of the blades, and I prefer to have them of the form, dimensions and proportions

5 shown in the drawings. Fins which diminish in width from the hub to the periphery do not produce as good results as fins which are wide at the periphery of the impeller. I have obtained the best results with fins having such area as to 10 reduce the effective intake area on the lower side of the impeller by 30%.

The apparatus effects a thorough and rapid intermixing and treatment of the liquid with the gas as explained in considerable detail in my 15 prior Patent 1,976,956. Additionally, the fins 30 act, as previously pointed out, to give the apparatus more uniform performance, particularly with respect to the gas suction effect occurring throughout a variation of liquid level in the tank. Also more uniform motor loading, and better overall performance thereby results.

The term "impeller" as used herein means a 20 rotating device which draws in liquid along lines of flow substantially parallel to the axis of rotation and discharges the major portion of the liquid in planes substantially perpendicular to the axis of rotation.

Various arrangements and proportions of the 25 fins 30 will produce the desired result in varying degrees but the drawings show the best proportions and arrangement which is now known to me.

I claim:

1. In apparatus for treating liquid with gases 30 of the type in which streams of liquid and gas enter a rotary impeller and are discharged by the impeller for circulation in a tank, the major portion of the discharge being in planes substantially perpendicular to the axis of rotation; the improvement which comprises: blades of the impeller being provided with trailing fins which occupy approximately 30% of the area between the blades.

2. In apparatus for treating liquid with gases 45 of the type in which a rotary impeller receives liquid from below and receives gas from above, the liquid and gas being mixed in the impeller and discharged therefrom for circulation in a tank, the major portion of the discharge being in planes substantially perpendicular to the axis of rotation; the improvement which comprises: lower portions of the blades of the impeller being provided with elongated trailing fins extending 50 lengthwise of the blades from adjacent to the center of the impeller to adjacent to the tips of the blades.

3. In apparatus for treating liquid with gases 60 of the type in which a horizontal rotary impeller receives liquid from below and receives gas from above, the liquid and gas being mixed in the impeller and discharged therefrom for circulation in a tank, the major portion of the discharge being in planes substantially perpendicular to the axis of rotation; the improvement which comprises: lower portions of the blades of the impeller being provided with trailing fins which 65 diminish the effective area of liquid intake from the bottom of the impeller by approximately 30%.

4. In apparatus for treating liquid with gases 70 of the type in which a horizontal rotary impeller receives liquid from below and receives gas from above, the liquid and gas being mixed in the impeller and discharged therefrom for circu-

lation in a tank, the major portion of the discharge being in planes substantially perpendicular to the axis of rotation; the improvement which comprises: lower edges of blades of the impeller being provided with trailing fins which extend lengthwise of the blades from adjacent to the center of the impeller to adjacent to the tips of the blades and are relatively wide adjacent to the tips of the impeller.

5. In apparatus for treating liquid with gases of the type in which a tank is provided with a submerged rotary impeller surrounded by a submerged hooded deflector ring, the impeller acting to draw liquid from below and draw both liquid and gas from above, the liquid and gas being mixed in the impeller and being discharged therefrom into the hooded deflector ring for ensuing circulation in the tank; the improvement which comprises: the impeller being of the forward discharge type and having its blades provided with trailing fins which reduce the effective intake area from below by approximately 30%.

10 6. In apparatus for treating liquid with gases of the type in which a tank is provided with a submerged rotary impeller surrounded by a submerged hooded deflector ring, the impeller acting to draw liquid from below and draw both liquid and gas from above, the liquid and gas being mixed in the impeller and being discharged therefrom into the hooded deflector ring for ensuing circulation in the tank; the improvement

which comprises: the impeller being of the forward discharge type and having the lower edges of its blades provided with trailing fins.

15 7. In apparatus for treating liquid with gases of the type in which a tank is provided with a submerged rotary impeller surrounded by a submerged hooded deflector ring, the impeller acting to draw liquid from below and draw both liquid and gas from above, the liquid and gas being mixed in the impeller and being discharged therefrom into the hooded deflector ring for ensuing circulation in the tank; the improvement which comprises: the impeller having the lower edges of the blades provided with trailing fins.

20 8. In apparatus for treating liquid with gases of the type in which a tank is provided with a submerged rotary impeller surrounded by a submerged hooded deflector ring, the impeller acting to draw liquid from below and draw both liquid and gas from above, the liquid and gas being mixed in the impeller and being discharged therefrom into the hooded deflector ring for ensuing circulation in the tank; the improvement which comprises: the impeller being of the forward discharge type and having the lower edges of the blades provided with trailing fins extending throughout the length of the blades, the fins being of substantial width adjacent to the tips of the blades and reducing the effective intake area from below by approximately 30%.

25 30 GORDON MACLEAN.
